UNITED STATES PATENT OFFICE.

WILLIAM H. CADWELL, OF NEW BRITAIN, CONNECTICUT.

COMBINED BOTTLE-CAP AND EXTRACTOR.

1,092,519.

Specification of Letters Patent.

Patented Apr. 7, 1914.

Application filed January 29, 1913. Serial No. 744,801.

To all whom it may concern:

Be it known that I, WILLIAM H. CADWELL, a citizen of the United States, residing at New Britain, in the county of Hartford and 5 State of Connecticut, have invented certain new and useful Improvements in Combined Bottle-Caps and Extractors, of which the following is a specification.

This invention relates to a combined bottle cap and extractor, among the principal objects of the invention being the provision of a simple article of this character which can be inexpensively and readily made, quickly applied to and removed from a bottle or jar and which has means for readily removing the paper cap or disk of a milk bottle or jar without possibility of the contents thereof scattering.

Referring to the drawings: Figure 1 is a perspective view of the upper portion of a milk bottle provided with a combined cap and extractor involving the invention. Fig. 2 is a sectional view of the same, less, however, of the bottle being shown.

Like characters refer to like parts throughout the several figures of the drawings.

In the drawings I have shown a portion of a glass bottle or jar such as is used at the present time for containing milk and which being of the ordinary character requires no detailed description. Said bottle or jar is equipped with a cap or closure such as that denoted in a general way by 35 3 and which may be made from any suitable material such for instance as sheet metal. The matter of material, however, from which the cap is formed is not altogether essential, for I will hereinafter describe a 40 cap of composite construction. Depending from the substantially flat body of the said cap or closure 3 is a flange 4 rounded somewhat to partially embrace or hug the external beaded portion of the bottle or jar 2 to thus effectually close the same against the admission of dust, germs and the like, thereby making the cap sanitary. This depending flange 4 may be furnished with several resilient tongues as 5 of which there 50 may be any desirable number and which are adapted to be sprung over the under side of the beaded portion of the neck to prevent accidental dislodgment of the cap 3 which, however, can be removed by comparatively 55 slight manual force.

One of the novel features of the invention is the provision of a cap extracting prong projecting from the periphery of the cap. In Figs. 1 and 2 this prong is denoted by 6 and is integral with the cap 3. Said cap 60 with the prong 6 and the clip members 5 can be readily made from sheet metal by the aid of suitable dies or otherwise. The prong 6 extends from the lower edge of the flange 5 and it is sufficiently pointed or 65 sharpened to permit its easy penetration of a paper cap or disk such as is now used on the average milk bottles or jars. It will be supposed that the jar 2 is full of milk or in fact any other beverage and that the same 70 is provided with one of these paper caps. Ordinary methods ordinarily used for removing these paper caps are usually followed with scattering of milk which frequently goes on the clothing. With the use 75 of the cap 3 provided with the extracting prong or barb this undesirable result can be prevented. To remove the paper cap the cap 3 is held at a slant thereto and the prong or barb 6 is pushed through the 80 paper cap or between the edge of the cap and the bottle rim at which point it becomes a simple matter to pry the paper cap from place when if it has been pierced by the barb or prong 6, it can be pulled or shaken 85 therefrom, and the cap 3 can then be applied. The prong or barb 6 does not project sufficiently beyond the periphery of the cap 3 to permit its being forced too far into the paper cap and the size of cap 3 is too great 90 for it to enter the neck of a milk bottle, therefore it cannot be pushed against one of the paper caps in such a manner as to force the latter into the contents of the bottle with the attendant undesirable result before mentioned.

What I claim is:

A bottle cap comprising a substantially flat circular body, and a circular flange depending from said body, said flange having 100 at its lower edge a barb extending outwardly at approximately a right angle to the axis of said body and also having several resilient clip members.

In testimony whereof I affix my signature 105 in presence of two witnesses.

WILLIAM H. CADWELL.
